SNATCH BLOCK

Filed Dec. 29, 1927

UNITED STATES PATENT OFFICE

NICHOLAI M. ERDAHL, OF EDGERTON, WISCONSIN, ASSIGNOR TO HIGHWAY TRAILER COMPANY, OF EDGERTON, WISCONSIN, A CORPORATION OF WISCONSIN

SNATCH BLOCK

Application filed December 29, 1927. Serial No. 243,284.

The invention relates to snatch blocks, and has for an object to provide a block of improved construction in which an intermediate portion of a cable may be quickly and easily positioned in or removed from the groove of the sheave at will. A further object is to provide means adapted to normally maintain the cable in engagement with the groove. It consists in certain features and elements of construction, herein shown and described, as indicated by the claim.

In the drawings:

Figure 1 is a face view of the snatch block embodying the present invention.

Figure 2 is a longitudinal sectional view taken substantially at a medial plane.

Figure 3 is a fragmentary sectional view of a modified construction.

In the drawing the snatch block is shown as comprising a unitary cast frame, 10, having two side members, 11 and 12, connected together at one end by a bottom portion, 13. A sheave, 14, is mounted between said side members on a bushing, 15, journaled on an inner bushing, 16, which is loosely mounted on a bolt, 17, journaled in bosses, 11^a and 12^a of the respective side members and held in place by a castellated nut, 18. The bushing, 15, is preferably of a self-lubricating type, to provide smooth and easy rotation of the sheave. The upper end of the side member, 12, extends beyond the sheave, forming a curved portion, 20, and terminating in a ring portion, 21; said ring portion being offset so as to be centrally aligned with a groove, 22, of the sheave, 14. The upper end of the side member, 11, also extends beyond the sheave and terminates in a hook shaped portion, 23, positioned within the plane of the groove, 22, and adapted to co-operate with the curved portion, 20, of the member, 12, to form a curved throat-way, 24, for a cable (not shown).

This throat-way, as may be seen from Figure 2, is provided with a mouth, 25, opening at one side of the block; the other end of said throat-way leading downwardly in substantial registration with the groove, 22, of the sheave. The width of said curved throat-way is such as to provide a slight force fit for the cable, so that any portion of the cable

may be quickly and easily snapped into and out of the sheave groove. When the cable is under tension it will at all times remain in the sheave groove; however, when the cable is slackened, it may tend to raise itself out of said groove, and in this event the slightly restricted, curved throat-way affords sufficient resistance to prevent the cable freeing itself from the block. Furthermore, if the cable assumes a whipping motion it will strike either the inside of the hook portion, 23, or against the inner wall of projection, 20, and be deflected laterally in the opposite direction. Of course it is understood that it will be necessary that the tension on the cable must be released in order that said cable may be removed from the block.

The side members, 11 and 12, and bottom, 13, are reinforced by a pair of integral ribs, 27, extending from said ring portion, 21, outwardly along the marginal edges of the member, 12, and bottom, 13, and upon the outside of the member, 11, to a point about central with the sheave bolt. The ring portion 21, is coupled with a shackle, 28, pivoted to an eye bolt, 29, for supporting the block in any convenient position. This connection is in effect a "universal" joint permitting the block to be swung about two axes, transverse of each other. The ring portion, 21, being offset for alignment with the sheave, permits the block proper to be supported in substantially true balance at all times.

My improved snatch block is of a type particularly adaptable for various rigging apparatus, such as hoisting, cable conveying apparatus, and the like, and especially for rigging, which must be set up and dismantled readily and frequently or in altering the set-up. The quick insertion and removal of a cable from the groove of the sheave, saves considerable time and inconvenience, which usually accompanies threading a cable through the block.

Figure 3, illustrates a modified construction, in which the upper end of the side member, 11, is recessed at, 31, for a spring guard member, 32, riveted to said side member. This spring guard is positioned with its hook-shaped end, partially registering with the

groove, 22, and co-operating with the curved portion, 20, to form a restricted throat-way, 33, considerably narrower than the cable, so as to permit the cable to be sprung into and out of the sheave groove. This spring guard is of sufficient stiffness to resist the tendency of the cable freeing itself from the block due to whipping, etc., and normally confine the cable in the groove. Of course the side members and spring guard may be made integrally of a single piece of stock, bent to the proper shape.

I claim:—

A snatch block including a substantially rigid frame consisting of two side members and a sheave mounted for rotation between them, one of said members having a portion extending beyond the periphery of the sheave and offset opposite the groove thereof, with a further extending portion formed for attachment to a support in a plane substantially central with respect to the sheave, the other side member extending inwardly adjacent the groove of the sheave and thence curving outwardly to cooperate with said offset portion of the first mentioned member to form a curved guideway opening at one side of the sheave for directing an intermediate portion of a cable into the groove of the same, and tending to prevent accidental dislodgment of the cable from the snatch block.

NICHOLAI M. ERDAHL.
